UNITED STATES PATENT OFFICE.

LOUIS H. PERLMAN, OF NEW YORK, N. Y.

WHEEL.

1,374,099.

Specification of Letters Patent.

Patented Apr. 5, 1921.

Application filed June 24, 1916. Serial No. 105,694.

To all whom it may concern:

Be it known that I, LOUIS H. PERLMAN, a citizen of the United States, residing at New York, in the county of New York and State of New York, have invented certain new and useful Improvements in Wheels; and I do hereby declare the following to be a full, clear, and exact description of the invention, such as will enable others skilled 10 in the art to which it appertains to make and use the same.

In the art of automobile wheels and more particularly in that branch of the art in which demountable rims appear, difficulty 15 has been experienced from a tendency to distort the rims and render them out of round by an excessive intrust of one of the locking wedges before the diametrically opposite locking wedge has been inserted, 20 and it is the primary object of the present invention to obviate this difficulty.

With this and further objects in view, as will in part hereinafter become apparent and in part be stated, the invention comprises certain novel constructions, combinations and arrangements of parts as subsequently specified and claimed.

In the accompanying drawing,—

Figure 1 is a transverse section through the peripheral portion of a wheel embodying the features of the present invention, the section being taken on a plane intersecting one of the wedges, the wedge and its bolt being seen in elevation.

Fig. 2 is a top plan view of the parts seen in Fig. 1 with the demountable rim and locking wedge removed.

Fig. 3 is a transverse axial section taken on the plane indicated by line 3—3 of Fig. 2.

Referring to the drawing by numerals, 1 indicates the wood felly which is, of course, provided with the usual spokes and hub, not seen. A felly band or fixed rim 2 is 45 shrunk, or otherwise fixed, on the felly 1, and is of the type provided with a cylindrical body portion terminating at its inner edge in a substantially conical stop flange 3. A demountable, tire-carrying rim 50 4 is adapted to have one of its edges rest on the flange 3 and its other edge supported on the locking wedges 5. Only one of the wedges 5 is shown in the drawing, but it is, of course, understood that an appropriate 55 number of such wedges is distributed uniformly about the periphery of the wheel

body as is the customary practice. A bolt 6 is anchored in the felly 1, for each locking wedge 5 and each of said wedges is provided with a pendent flange 7 apertured to receive said bolt and the flange itself being engaged by a nut 8 threaded onto the bolt 6.

The structure as thus far described may be considered conventional in form and may follow the lines of any of the well known 65 types.

It will be perfectly obvious to any one skilled in this art that when an operator has applied the rim 4 and positioned the several locking wedges 5 and then begins 70 to screw up the nuts 8, if he screws up one nut until this wedge 5 is forced in the maximum distance, the rim 4 will be distorted and the tightening of the other nuts will not relieve the out of round condition of 75 the rim 4 as the intrust of the several remaining wedges cannot be as great as that of the first wedge. This is true because in the demountable rim structures in common use today there is no provision made for 80 limiting the extent of intrust of each of the locking wedges, except such limitation as arises from contact of the pendent flange of the wedge with the edge of the felly band.

The difficulty just mentioned is entirely overcome by the present invention which provides means for limiting the maximum intrust of any wedge to substantially that point represented by the final seated position of the demountable rim when all of 90 the wedges are in their final locking conditions.

The character and method of connection of the stop is susceptible of wide variation, 95 but I find one very simple and yet efficient means of providing for such stop consists in stamping the material of the felly band 2 outward immediately in the rear of each wedge 5 producing an outstanding plate 9. 100 To give the plate 9 perfectly straight edges, the material of the felly band 2 is slit along the lines 10, 10 before the plate 9 is stamped out so that the ends of the plate only remain connected with the felly band 2. The 105 plate 9 may be of various lengths and may extend outward to different distances as may be found desirable, but I consider it preferable to have the plate 9 approximately of a length equal to the width of the inner 110 edge of the wedge 5 and to outstand a distance less than the effective thickness of the

wedge but greater than the distance from the outer face of the felly band to the outer face of the tip of the wedge. This insures against the nose or tip of the wedge riding 5 over the stop which would be objectionable for a number of reasons.

It will thus be seen that the stops 9 are located at that distance from the outer edge of the felly band 2 represented by the full 10 extent of inward travel of the tip of the wedge 5 when the wedge is moved to that final position represented by the corresponding final position of all of the wedges and a uniform distention of the rim 4 by said 15 wedges, and by being so located the stops 9 serve to prevent the operator from thrusting one of the wedges too far beneath the demountable rim and thus prevent the next or a diametrically opposite wedge from 20 entering as far. In this way the stops 9 insure a location of the several wedges which is uniform both in the matter of tensioning the rim 4 and of sustaining the same in a perfectly circular condition. Furthermore, 25 the stops 9 have the advantage of providing a dead stop for the several wedges 5 which, upon being reached, enables the operator to discontinue further inward thrust of the nut 8 with the assurance that the nut has reached 30 its final position and without the liability of stripping the nut.

That edge of felly band 2 provided with flange 3 is referred to as the inner edge since it is the edge next to the car body when the 35 wheel is applied to an automobile, and the opposite edge is for the same reason referred to as the outer edge. The direction radially away from the axis of the wheel may also properly be called "outward" and the distinction 40 between that direction and the outer portion of certain parts, referring to the outer face of the wheel, will be apparent from the context.

What I claim is:—

45 1. The combination with a wheel body and a demountable rim therefor, of wedges for locking the demountable rim on the wheel body and stops disposed in the path of the free edges of the wedges for limiting the 50 thrust thereof.

2. The combination with a wheel body adapted to sustain a demountable rim, and

securing means for the rim comprising a wedge, of a stop outstanding from the periphery of the wheel body into the path of 55 travel of the wedge.

3. The combination with a wheel body adapted to sustain a demountable rim, and securing means for the rim comprising a wedge, of a stop stamped from the material 60 of the wheel body and outstanding from the periphery thereof into the path of travel of the wedge.

4. The combination with a wheel body having a metallic felly band provided at 65 its inner edge with an outstanding stop flange and a demountable rim having one edge adapted to rest on said flange, of securing means for the rim comprising a wedge adapted to sustain the other edge of the 70 demountable rim and to itself rest on the outer edge portion of the felly band, and a stop stamped from the felly band outward into the path of the wedge in position for limiting the extent of inward movement 75 thereof.

5. The combination with a wheel body having a metallic felly band provided at 80 its inner edge with an outstanding stop flange and a demountable rim having one edge adapted to rest on said flange, of securing means for the rim comprising a wedge adapted to sustain the other edge of the 85 demountable rim and to itself rest on the outer edge portion of the felly band, and a stop stamped from the felly band outward into the path of the wedge in position for limiting the extent of inward movement 90 thereof, said stop comprising a plate having a flat edge presented toward the wedge.

6. In a wheel structure, the combination with a felly band, a rim adapted to be demountably positioned on the felly band and securing means for the rim comprising a wedge for locking the rim on the felly band, 95 of means between the felly band and rim for limiting the movement of the wedge.

In testimony whereof I affix my signature in presence of two witnesses.

LOUIS H. PERLMAN.
